UNITED STATES PATENT OFFICE.

JAMES M. JELLISON, OF BOSTON, MASSACHUSETTS.

DESIGN FOR A DRAWER-PULL.

SPECIFICATION forming part of Design No. 21,171, dated November 10, 1891.

Application filed July 20, 1891. Serial No. 400,160. Term of patent 14 years.

To all whom it may concern:

Be it known that I, JAMES M. JELLISON, of Boston, in the county of Suffolk, State of Massachusetts, have invented and produced 5 a new and original Design for Drawer-Pulls, of which the following is a description sufficiently full, clear, and exact to enable any person skilled in the art or science to which said invention appertains to make and use 10 the same, reference being had to the accompanying drawings, forming part of this specification, in which—

Figure 1 is a front elevation of my design for a drawer-pull, and Fig. 2 is a vertical 15 transverse section of the same.

The leading feature of my design consists of a concavo-convex plate provided with beads at its top, bottom, and center, with curved depressions between the beads, an inclined top, and an inclined arm.

The concavo-convex plate A is provided at 20 its lower portion with a semicircular bead d, and resting upon this bead is a rabbet f. A

curved depression g connects the rabbet f with another rabbet i under the central bead 25 h. Another rabbet i' rests upon this bead h, and a curved depression j connects this rabbet with a third rabbet i'', which is connected to the top bead k, and above this bead is a convex top m. The central bead h is slightly 30 smaller than the lower bead d. An inclined arm B extends from the top at one side of the center and is provided with a head.

I claim—

The design for a drawer-pull herein shown 35 and described, the same consisting of a concavo-convex plate provided with beads at its top, bottom, and center, said plate having curved depressions between said beads, an inclined top, and an inclined arm extending 40 upward from said top.

JAMES M. JELLISON.
